(57) **CLAIM**

The ornamental design for a heat seal machine, as shown and described.

DESCRIPTION

FIG. 1 is a side elevation of a heat seal machine embodying my design;

FIG. 2 is a front view of a heat seal machine embodying my design;

FIG. 3 is a rear view of a heat seal machine embodying my design;

FIG. 4 is a top view of a heat seal machine embodying my design;

FIG. 5 is a bottom view of a heat seal machine embodying my design; and,

FIG. 6 is a perspective view of a heat seal machine embodying my design.

The broken lines in the several figures of the drawings are for illustrative purposes only and form no part of the claimed design.
